United States Patent Office.

ROBERT GRACEY, OF PITTSBURG, PENNSYLVANIA.

Letters Patent No. 83,376, dated October 27, 1868.

IMPROVED BOLT-HEADING MACHINE.

The Schedule referred to in these Letters Patent and making part of the same.

To all whom it may concern:

Be it known that I, ROBERT GRACEY, of the city of Pittsburgh, in the county of Allegheny, and State of Pennsylvania, have invented a new and useful Improvement in Apparatus for Operating Bolt-Heading Dies; and I do hereby declare the following to be a full, clear, and exact description thereof, reference being had to the accompanying drawing, making a part of this specification, in which—

Figure 1 is a side elevation of my improved apparatus for operating bolt-heading dies, and

Figure 2 is an end elevation of the same.

Like letters of reference indicate like parts in each.

The nature of my invention consists, first, in the construction and combination of devices for operating by steam a weighted drop-beam, by which, through a toggle, the heading-die of a bolt, spike, or rivet-machine is operated; and, second, in combining with such devices, an adjustable bumper-head, so as thereby to regulate the length of stroke of the heading-die, and thus, without other adjustment of the machine, to make bolt-heads of different sizes.

To enable others skilled in the art to make and use my invention, I will proceed to describe its construction and operation.

A is a single acting steam-cylinder, fitted with a piston, of any convenient construction, on the under side only of which steam is admitted, through a single-acting slide-valve in the valve-chest d.

By a steam-pipe, n', steam is supplied to the valve-chest d, and the exhaust steam escapes from the cylinder A, by an exhaust-pipe, n, connected therewith by suitable passages.

M is a shaft, resting in properly-constructed bearings, and fitted with suitable gearing, through which power is communicated, to secure the motions presently to be described.

To the arms d' d', attached to the valve-chest d, or to some other fixed object, the levers a a' are pivoted, the former, a, by its extreme end, the latter, a', midway between its ends.

The valve-stem c connects the slide-valve, in the valve-chest, with the levers a a', by which it is operated.

These levers a a' are actuated by trippers b b', which are fastened to the shaft m, and revolve therewith.

At each revolution, the tripper b' engages the lever a, and gives the stem c and the slide-valve a downward throw. The tripper b next engages the lever a', and raises the valve, the steam thus being admitted to the cylinder, to operate the piston therein, and then being exhausted in the usual way.

At or near the opposite end of the machine (all the devices named being supported on any suitable frame or foundation, m) is a post, L, to the upper end of which, as a fulcrum, is pivoted the drop-beam F, which, in turn, is connected to the piston, in the cylinder A, by a link, H.

B B are guides, playing vertically through guide-boxes h h, by which a vertical motion is secured to the piston.

On the forward end of the beam F are hung one or more weights, f, to increase the effectiveness of its downward percussive blow.

Between the fulcrum-post L and cylinder A, the link G connects the beam F with the toggles K K', the latter, K', moving on a fixed point, at k, and the former, K, being attached to a heading-die, N.

To the bumper-posts E E, I attach the bumper-head J, and make it adjustable thereon by the nut o.

In a recess in this bumper-head is a cushion, D, of India rubber, or other yielding, elastic material.

The lower end of such recess is closed by a piston, j, which is held in place by a stem, e, passing through the cushion D and bumper-head J, and secured by a nut, e'.

By the revolution of the shaft M, the tripper b is brought against the lever a', moving the slide-valve in the valve-chest d, admitting steam into the cylinder A, below the piston, forcing it and the drop-beam F upward, until the latter strikes the piston j in the bumper-head J. This motion raises the link G, and draws back the toggle K, and the heading-die N attached thereto. The iron for the bolt is then fed in between suitably-shaped gripping-dies, s, by which it is seized and securely held.

By the continued revolution of the shaft M, the tripper b' and lever a give the slide-valve a throw, in the opposite direction, and open the exhaust-port, when the steam escapes from below the piston, the weighted drop-beam F falls, the toggle K forces the heading-die or tool N backward, and upsets a head, x', on the end of the bolt x. The bolt is still held by the gripping-dies, till the heading-tool N is withdrawn, when it is discharged, the material for another bolt fed in, and the operation continued as before.

In order to make bolt-heads of different sizes, I adjust the bumper-head J higher or lower, by the nuts o. By lowering this bumper-head J, the beam F has less motion, the toggle K and header N are drawn back a less distance, and consequently a less length of bolt-rod is fed in, and a head of smaller size is formed.

To make a larger bolt-head, the bumper-head J is raised, and the header N is drawn further back.

The header N of course should be changed for bolts of different-sized heads.

The trippers b b' are so adjusted on the shaft M as to open the exhaust-port, when the drop-beam F strikes the bumper-cushion j, and also so as to close the exhaust-port and admit steam, in time to cushion the piston when it comes down with the fall of the drop-beam F.

The steam-cylinder A, with the slide-valve, and the devices for operating it, may, of course, have any desirable position relative to the drop-beam F, above or

below, or at any other point where it will secure substantially the same operation.

What I claim as my invention, and desire to secure by Letters Patent, is—

1. The weighted lever F, link G, and toggle-arms K K', in combination with the header N, and steam-cylinder A, arranged and operating substantially as described.

2. An adjustable spring bumper-head, J, arranged in relation to the weighted drop-beam F, toggles K K',

and piston in steam-cylinder A, for regulating the throw of bolt-heading dies, substantially as and for the purposes hereinbefore set forth.

In testimony whereof, I, the said ROBERT GRACEY, have hereunto set my hand.

ROBERT GRACEY.
